US0D1052712S

(12) **United States Design Patent** (10) **Patent No.:** **US D1,052,712 S**
(45) **Date of Patent:** **** Nov. 26, 2024**

(54) **DEHUMIDIFIER**

- (71) Applicant: **Samsung Electronics Co., Ltd.**, Suwon-si (KR)
- (72) Inventors: **Hyunsoo Kim**, Suwon-si (KR); **Taeahn Kim**, Suwon-si (KR); **Yeaseul You**, Suwon-si (KR); **Minkyung Choi**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/878,757**
- (22) Filed: **Jun. 27, 2023**

(30) **Foreign Application Priority Data**

- May 25, 2023 (KR) 30-2023-0020003
- (51) LOC (14) Cl. 23-04
- (52) U.S. Cl. USPC **D23/359**

(57) **CLAIM**

The ornamental design for a dehumidifier, as shown and described.

DESCRIPTION

FIG. 1 is a front perspective view of a dehumidifier, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an enlarged view of the portion 9 in FIG. 1;

FIG. 10 is an enlarged view of the portion 10 in FIG. 6; and, FIG. 11 is an enlarged view of the portion 11 in FIG. 8.

The even-dash broken lines illustrating portions of the dehumidifier form no part of the claimed design. The dot-dash broken lines encircling enlargement portions of the claimed design form no part of the claimed design.

1 Claim, 11 Drawing Sheets
